[57] CLAIM

The ornamental design of an electrically driven screw driver, substantially as shown and described.

DESCRIPTION

FIG. 1 is a front elevational view of an electrically driven screw driver showing my design;
FIG. 2 is a rear elevational view thereof;
FIG. 3 is a leftside elevational view thereof;
FIG. 4 is a rightside elevational view thereof;
FIG. 5 is a top plan view thereof;
FIG. 6 is a bottom view thereof; and
FIGS. 7 and 8 are perspective views thereof respectively.
